C. F. SIMONSEN

HINGE JOINTED LEGGING

Filed Dec. 22, 1924

FIG. 1

FIG. 2

Patented Sept. 7, 1926.

1,599,295

UNITED STATES PATENT OFFICE.

CHRISTIAN FERDINAND SIMONSEN, OF DUNEDIN, NEW ZEALAND.

HINGE-JOINTED LEGGING.

Application filed December 22, 1924, Serial No. 757,478, and in New Zealand September 30, 1924.

The objects of my invention are to provide a means for easily and securely fastening leggings, to make the same practically watertight, to provide a securing means which, during the walking of the wearer, will not catch any objects such as long grass or the like, and to provide against the loss of the fastening pin when the said leggings are not in use. For these purposes I make the leggings without any metal work, except a long pin and an eyelet to hold the upper end of same, without wear to the material. The fastenings at the meeting edges of the legging are in the form of butt hinges, and a flap is secured to the inner side of the legging adjacent each of its meeting edges, the flap adjacent one of said edges being narrower than that at the other edge and being adapted to enter between the wider flap and the fastening adjacent such wider flap, thus forming a practically water-tight joint, while the hinge-like joint is, at the same time flexible and lies flat without any projections to catch in anything if the wearer passes through such.

Referring to the accompanying drawing:—Figure 1 is a view in elevation of a legging showing the hinge-like joint and pin complete. Fig. 2 is a similar view, showing the meeting edges of the legging apart. Fig. 3 is an enlarged sectional view showing the meeting edges of the legging drawn apart and the flaps attached to same, in relation to each other, for producing a tight joint.

A is the part of the legging coming from the back, and A¹ the narrow flap attached to said part adjacent its edge, A² is the other part of the legging coming from the front and A³ is the wider flap secured to the part A² adjacent the edge of the latter part. The flap A¹ of the other part A of the legging is adapted to enter between the flap A³ of the part A² of the legging and the fastenings carried by said part A² and thus form a substantially water-tight joint at the meeting edges of the two parts A and A² of the legging. A hinge-pin B extends through the whole length of the joint between the two meeting edges of the legging and has its lower end B² pointed in order to facilitate its insertion in the eyes of the fastenings. The upper end of the pin B is bent into an eye B³ to form a convenient handle for the finger when inserting the pin in and removing it from the fastenings and is then turned sharply to form a stud B¹ adapted to enter an eyelet C formed in the legging adjacent the upper end of one of its meeting edges in order to maintain the pin in position. E are the portions of the hinge attached to the end A, and E¹ is a long plain pocket, shown dotted in Figs. 1 and 2, in which the pin B may be inserted when the legging is not in use. E² are the portions of the hinge formed in the edge of the part A² of the legging.

The hinge-like fastening parts at the meeting edges of the legging comprise ears, each having a longitudinally-extending eye at its free end to receive the hinge pin B. These ears are formed by a plurality of cuts made longitudinally of the legging adjacent each edge of the latter a suitable distance back of said edges and by cuts extending from said edges to said longitudinal cuts at an inclination to said longitudinal cuts. By reason of this formation of the ears the fastenings on one of the meeting edges of the legging are adapted to more easily enter between the complementary fastenings formed on the other meeting edge of the legging than they would be if the cuts which extend at an inclination to the longitudinal cuts extended at a right angle to the longitudinal cuts. This is particularly true when the legging becomes wet and the ears are caused to swell. The construction of fastenings just described might be impractical if any substantial hinge action between the meeting edges of the legging were required, but it is essential to this invention, since practically no hinge action is required in the legging joint as set forth. Also the flap A³ is attached to the part A² of the legging at a sufficient distance back from the edge of the latter to allow the flap A¹ of the other part to enter between the flap A³ and the fastening of the legging adjacent the latter. Thus with the tightly fitting hinge parts, the two flaps make a water proof joint without any place for foreign substances to catch on, or get between. My leggings are so flexible that they are interchangeable, so that the legging may be worn with the fastening on either the inner or outer side of the leg.

The legging may be made in any size and of any suitable material.

Having now described and explained my invention what I claim and desire a patent of the United States of America for is:—

1. A legging having on each of its meet-

ing edges a plurality of ears formed by aligned cuts extending longitudinally of the legging a suitable distance back of each of its meeting edges and by cuts extending 5 from such meeting edges to said first named cuts at an inclination to the latter, said ears having at their free ends longitudinally extending eyes, the ears of one of said meeting edges being adapted to extend into the cut 10 away portions of the other meeting edge with the eyes of the former in alignment with the eyes of the latter.

2. A legging having at each of its meeting edges a plurality of hinge-like fastenings 15 each having a longitudinally extending eye at its free end, the fastenings at one of said edges being adapted to enter between the fastenings of the other edge with the eyes of said fastenings in alignment, said legging 20 having an eyelet formed adjacent one end

of one of its meeting edges, and a pin for insertion through the eyes of said fastenings for securing said meeting edges together, said pin having one of its ends bent to form a finger loop and provided with a 25 stud adapted to enter said eyelet for securing said pin in place.

3. A legging having its meeting edges provided with means for securing said edges together and having a flap secured to its 30 inner side adjacent each of said edges, one of said flaps being shorter than the other and adapted to enter between the other flap and the fastenings adjacent the latter to form a substantially water-tight joint be- 35 tween said meeting edges.

In testimony whereof I have hereunto set my hand.

CHRISTIAN FERDINAND SIMONSEN.
